United States Patent Office

Des. 182,727
Patented May 6, 1958

182,727

DISPLAY STAND

Thaddeus I. Kingsford, Atlanta, Ga., assignor to Scripto,
Inc., a corporation of Georgia

Application December 18, 1957, Serial No. 48,948

Term of patent 14 years

(Cl. D80—9)

Fig. 1 is an elevational view of the display stand illustrating my new design;

Fig. 2 is a top plan view of the display stand shown in Fig. 1;

Fig. 3 is a perspective view thereof; and
Fig. 4 is a bottom plan view.

I claim:

The ornamental design for a display stand, as shown.
